APPARATUS FOR AND THE METHOD OF
CONTROL AND UTILIZATION OF DRY ICE

James G. Scott, Washington, D. C.

Application September 2, 1949, Serial No. 113,811

4 Claims. (Cl. 62—91.5)

1

This invention relates to apparatus for and the method of control and utilization of Dry Ice, and particularly to structure and a method intended and adapted for use and employment with solidified carbon dioxide or similar solidified refrigerant as now ordinarily commercially supplied in blocks or cakes.

The primary purpose of this invention is to provide a refrigeration cycle particularly adaptable to use and accomplishment with apparatus for and the method of control and utilization of Dry Ice or solidified carbon dioxide.

An object is to provide apparatus and a method for utilization and control of temperatures as attained by sublimation of a block or cake of solidified carbon dioxide, to attain and restrain and maintain desired refrigerating temperatures within usable ranges, in a storage case or other refrigerating apparatus or appliance.

Another object is to provide apparatus to receive and efficiently employ solidified carbon dioxide as a refrigerant, which apparatus employs the gas of sublimation to refrigerate and to aid in insulation and in warding off and preventing heat infiltration into a refrigerated compartment or space.

Another purpose is to provide apparatus which will efficiently employ a block of solidified carbon dioxide to attain and maintain a desired and predetermined temperature, within usable commercial ranges, with the sublimation controlled to expenditure of the energy of the solidified carbon dioxide only as required, without the necessity of venting off or wasting the usually excess energy of a block of material as ordinarily employed.

Still another purpose is to provide a method whereby a block of solidified carbon dioxide can be employed to give a desired predetermined temperature within commercially usable range, within a compartment to be refrigerated, and to maintain a substantially uniform and constant temperature within the compartment throughout substantially the entire life or existence of any substantial portion of the block of solidified carbon dioxide or refrigerant.

Yet another object is to provide apparatus and a method whereby a substantially uniform governed temperature and a predetermined definite time or length of refrigeration can be attained and maintained efficiently and economically, and without waste or creation of excessively low temperatures, by the use of solidified carbon dioxide.

Another purpose is to provide apparatus in which solidified carbon dioxide may be employed

2

as a refrigerant, which apparatus will give desired regulated temperature within a refrigerated or storage space or compartment and will assure and will maintain a circulation of air within the compartment.

A further object is to provide apparatus and a method capable of embodiment and use in refrigerating apparatus, such as a pie case employed for transportation of pies or for counter display and dispensing of such pies, which will give a desired temperature to preserve the pies in oven-fresh condition, and which in fact will serve to temper or condition the pies so that the crust will not become soft or soggy but will retain its original flakiness and condition, the apparatus and the utilization of the solidified carbon dioxide being such that the pies are tempered and are preserved, and usually perishable meringues and whipped cream and other toppings will be maintained against dehydration and loss of color and loss of texture and other deteriorating effects heretofore resultant from the handling or storage of pies in usual containers, whether refrigerated or not.

20

Still another purpose is to provide an apparatus for use in handling and storing pies, which has supporting rack structure assuring carrying and storage of a number of pies, and which has parts adaptable for adjustment to accommodate various sizes of pies, as for example 8-inch pies, 9-inch pies, and pies of 10-inch diameter, or larger or smaller.

25

Another purpose is to provide refrigerating apparatus for using solidified carbon dioxide, in which the gas of sublimation is confined and is circulated by its inherent weight and natural flow and pressure to substantially circulate and fill a tortuous path or course through the hollow wall up around the refrigerated compartment, and thus consequently presented entirely outside of the compartment but in the refrigerating and insulated wall thereof to thus refrigerate and at the same time to exclude and carry off heat of infiltration that would otherwise be encountered through the walls of the compartment.

30

Yet another object is to provide apparatus and a method with which the Dry Ice is in a closed compartment and gas of sublimation is accumulated and generates pressure to circulate the cold gas as a refrigerating medium on the outer side of a wall of the refrigeration compartment and in a path and manner to keep the wall cold to absorb heat from the compartment and at the same time to carry away heat of infiltration through the insulated wall.

With the above and other objects in view, some of which will be apparent to those skilled in the art, and others of which are inherent in the use and construction of my improved apparatus and in the carrying out of my improved method, my present invention includes certain novel features of construction and assembly of parts, and certain new steps in the carrying out of the method or process; and certain new features in the apparatus, which will be hereinafter set forth in connection with the drawings and then pointed out in the claims.

The invention will appear more clearly from the following detailed description when taken in connection with the accompanying drawings, showing by way of example one embodiment of my invention.

In the drawings:

Figure 1 is a view in perspective showing a cabinet structure, such as a pie transportation or storage and sales case, embodying my invention.

Fig. 2 is a vertical sectional view taken transversely through the apparatus as illustrated in Figure 1.

Fig. 3 is a horizontal sectional view.

Fig. 4 is a partial perspective view showing one door open and with a pie rack in place.

Fig. 5 is a vertical sectional view taken from front to back through the apparatus.

Fig. 6 is a perspective view showing the central circulating column with the refrigerant container at the top thereof, as embodied in a pie storage or transporting case, and with parts in dotted lines to better show relative position of the parts.

Fig. 7 is a fragmentary view in front elevation of one form of pie rack.

Fig. 8 is a view in top elevation of the rack as shown in Fig. 7.

Fig. 9 is a top plan view showing a modified construction of pie rack.

Fig. 10 is a top plan view showing another modified construction of pie rack.

Fig. 11 is a fragmentary front elevational view of the pie rack as shown in Fig. 10.

In the presently illustrated embodiment of my invention, I have illustrated and disclosed a case for containing pies as these are transported or are held for sale, or are displayed and dispensed. In the present instance, I have disclosed the cabinet structure 1, as having two refrigerating compartments, 2 and 3, these compartments being closed by doors 4 and 5. An air circulation stack 6 is provided intermediate the refrigerating compartments 2 and 3, and a relatively narrow refrigerant container or compartment 7 is disposed in the middle of the upper portion of this air circulating stack 6. The container or compartment 7 is disposed with its ends separated from the front and back of the air circulating stack 6, and has its top open for reception of a block or slab of solidified carbon dioxide refrigerant. A door opening 8 is provided in the top of the cabinet structure to give access through the open top of the refrigerant container or compartment 7, and a door 9 is provided to close the opening 8 and to close and substantially seal the refrigerant container or compartment 7 to be gas-tight and leak-proof.

The cabinet structure 1 is substantially open on the forward or door side, and the other three sides as well as the top and bottom are provided with outer insulation. The refrigerating compartments 2 and 3 are defined by a wall structure 11, of sheet metal or other suitable material,

which is spaced from the insulation material 10 so that gas spaces are provided at 12 and 13, at the bottom and top of the wall structure 11, and at 14 and 15 on the sides of the refrigerating compartments 2 and 3, and at 16 on the back of these compartments. The gas space as thus provided is sealed or made gas-tight, and the only outlet therefrom is through a gas escape vent 17, opening from the top gas space 13.

As shown in Fig. 2 of the drawings, the refrigerant container or compartment 7 is made relatively narrow and tall, so that the sides of this refrigerant compartment are spaced inwardly from the inner sides of the air circulation stack 6, and upper air passages 18 and 19 are provided through the upper parts of the walls of the stack 6, at the sides, so that these open from the refrigerating compartments 2 and 3. Lower air passages 20 and 21 are provided through the side walls of the stack to open from the stack into the lower parts of refrigerating compartments 2 and 3. The air circulation stack 6 is entirely within the wall structure 11, and there is of course no communication from any part of the gas space around this wall 16, to the interior of the refrigerating compartments 2 and 3.

The refrigerant compartment 7 is tightly closed so that gas of sublimation of the solidified carbon dioxide will not and cannot find its way into the refrigerating compartments 2 and 3. As the refrigerant container or compartment 7 has the side and end walls thereof entirely separated from the walls of the stack 6, and consequently not in contact with any part of the walls of the refrigerator or cabinet structure, there will not be any appreciable heat exchange between the side and end walls of the refrigerant container 7, and sublimation of the block of solidified refrigerant can be accurately gauged and governed and controlled, since heat exchange is substantially confined to the bottom wall of the refrigerant container or compartment 7, and the block or cake or slab of carbon dioxide refrigerant is out of contact with all other walls of the refrigerant compartment or container 7.

This refrigerant compartment 7 is provided on its bottom with a heat exchange wall 22 of metal, or other material found suitable for the purpose, and it is through this wall, primarily, that the air within the refrigerating compartments 2 and 3 is cooled and is circulated. The side and end walls of the refrigerant container or compartment 7 are exposed in the upper part of the air circulating stack 6; but, these side and end walls are not primarily depended upon as heat exchange walls, and the control and utilization of the Dry Ice or solidified carbon dioxide is accomplished primarily through the bottom heat exchange wall 22. Dry Ice is now commercially supplied in cakes of more or less standard size, and these cakes are cut up into slabs or thin blocks, of desired shape and size, for better commercial utilization. In the carrying out of my invention, I purposely make the refrigerant container or compartment 7 tall and narrow so that when a slab or thin block of Dry Ice is placed therein, this thin block will be stood on one edge to rest upon the heat exchange wall 22, or upon insulating material placed therein after the manner and for the purpose herein-after more fully described. Thus, the Dry Ice block or cake or thin slab has only one surface thereof in contact with the refrigerant compartment, and that is the lower thin edge face which is in contact with or proximity to the heat

exchange wall 22 in the bottom of the refrigerant compartment.

Downwardly inclined air deflecting vanes 23 and 24 extend from the inner sides of the side walls of the air circulation stack 6, below the refrigerant compartment 7, so that air taken in through the upper air passages 18 and 19 and then cooled by contact with the heat exchange wall 22 will be deflected and directed to the middle of the air circulation stack 6 and will then drop and flow downwardly within this stack to circulate into the lower part of the refrigerating compartments 2 and 3, through the lower air passages 20 and 21. These air deflecting vanes 23 and 24 will cause the air to sweep across the under side of the heat exchange wall 22, and the absorption of heat through this wall will cause the cold air to then drop downwardly along the inclined air deflecting vanes 23 and 24, and to circulate after the manner shown by the arrows.

On the lower side of the heat exchange wall 22, I provide a plurality of heat exchange fins 25, which extend transversely across and depend from the heat exchange wall 22, so that these heat exchange fins are directly in the path of flow of the circulated air as this is directed inwardly by the air deflecting vanes 23 and 24. While I have stated that a plurality of these heat exchange fins 25 will be provided, the size or width of these fins and the number of fins can be varied to increase and decrease the heat exchange surfaces and areas as thus presented, and in this way the temperature of the circulated air can be controlled and can be varied. For example, to accomplish a lower temperature the heat exchange fins 25 can be made wider, or of heavier metal or other suitable material, and a greater number of these fins can be employed, thus increasing the heat exchange surfaces as presented in the path of flow of the circulated air. The heat exchange fins are associated with the heat exchange wall 22 in such manner that a direct heat exchange effect is accomplished, and as stated, the temperature to be accomplished within the refrigerating compartments 2 and 3, by circulation of air therein, can be varied and can be accurately controlled by variations in the size and number of the heat exchange fins. This is possible because the thin block or slab of Dry Ice within the refrigerant compartment has a thin lower edge, of predetermined and constant size, resting upon or adjacent to the heat exchange wall 22.

As has been stated, the refrigerant compartment 7 is closed or sealed so that the gas of sublimation will not escape into the refrigerating compartments 2 and 3, or into the air circulating through the stack 6, and since it is desired that this gas of sublimation be supplied direct to the gas spaces at the bottom, I provide a gas conducting or escape tube 26 from the compartment 7 extending down and opening into the bottom gas space 12. This gas escape or conducting tube 26 has its inlet end opening from the refrigerant compartment 7 well up toward the top thereof, and thus gas will fill the refrigerant compartment 7 and will surround the cake or slab of solidified carbon dioxide. Since carbon dioxide gas is heavier than air, the gas resulting from sublimation of the solidified carbon dioxide, through contact with the heat exchange wall 22, will fill up within the compartment 7 and will then run over and will descend through the gas escape or conducting tube 26 to flow into the

gas space 12 at the bottom of the apparatus. As the quantity of gas increases the space within the sides, at 14 and 15, and the gas space in the back, at 16, and the gas space at the top, at 13, will be filled with the carbon dioxide gas. The gas escape vent 17 is placed near the top so that there will be no escape of gas until all gas spaces are filled, and the vent will then function only to permit escape of such gas as may not be required for efficient insulation and maintenance of the gas charge within the gas spaces.

With this construction and arrangement and functioning of the parts, the block or slab of solidified carbon dioxide can be made with the face thereof resting upon or in proximity to the heat exchange wall 22, of a predetermined size which will give a measured and governed sublimation and consequently will permit measured and accurate control of temperatures. Also, since heat absorption has been found to occur primarily from this lower face of the solidified carbon dioxide, it is possible to measure and calculate the useful life of a charge of solidified carbon dioxide by making the slab or block of refrigerant of a desired and predetermined height. In this way, the useful life and refrigerating period of a charge of solidified carbon dioxide can be controlled and can be determined.

With the construction and functioning of the parts, in the manner set forth, the gas of sublimation will first fill the refrigerant container or compartment 7, thus giving a surround atmosphere of the inert gas, and as the gas of sublimation increases within this compartment 7, the gas will then flow downwardly through the gas conducting or escape tube 26 and will fill the entire space around the walls of the refrigerating compartment. By experiments and tests, I have found that an atmosphere of carbon dioxide gas confined between walls is a much more efficient insulator than dead air or any commercial insulation, and that the confined carbon dioxide gas is perhaps second only to a vacuum or exhausted space, in refrigerating efficiency. Further, I have found that where the carbon dioxide gas is conducted and is confined in the manner set forth, refrigerant of the compartment is accomplished through the walls, and there is an appreciable hold-over refrigeration temperature when the block of solidified carbon dioxide is substantially reduced in size or exhausted. I have accomplished very efficient results by employment of two inches of outside insulation, and the insulating effect resulting from confining the carbon dioxide gas in a one-inch wall space opening, but it will be appreciated that these dimensions can be varied to suit the different requirements of use.

It has been found that the gas of sublimation leaving the block of Dry Ice or solidified carbon dioxide is only substantially 10 degrees warmer than the temperature of the block, it being known that the temperature of Dry Ice is 110 degrees below zero, Fahrenheit. As the gas of sublimation is substantially heavier than air, being approximately one and one-half times the weight of air, there is a natural tendency for the gas of sublimation to accumulate within the refrigerant compartment or container, and within the open wall space around the refrigerating compartment; but, it must be taken into account that through circulation of air within the refrigerating compartment and over the heat exchange wall 22, sublimation of the Dry Ice within the closed and sealed refrigerant compartment 7 is continuing.

This continued sublimation accumulates gas within the closed and sealed compartment 7, and then forces the gas through the tube 26 down into the bottom space around the refrigerating compartments, and upwardly between the side walls. Since this gas is of low temperature, the side walls of the refrigerating compartment become in effect heat exchange walls, and even after the doors of the refrigerating compartment have been opened to give access to the contents thereof, there will be a rapid pick-up of refrigeration and a rapid lowering of temperature within the refrigerating compartment. The air circulating within the refrigerating compartment contacts the heat exchange wall 22, causing sublimation of the Dry Ice, and consequent flow of gas upwardly between the hollow walls around the refrigerating compartment, and this circulating cold gas will aid in refrigeration and in stabilizing temperatures because the side walls of the refrigerating compartments are in effect cold heat exchange walls. At the same time, the cold gas forced upwardly within the hollow wall will intercept and will carry off any heat of infiltration that might otherwise reach the refrigerating compartment through the side walls of the cabinet structure.

By experiments and tests, I have determined that where the gas of sublimation leaving the block of Dry Ice may have a temperature of around 100 degrees below zero, Fahrenheit, I can employ this cold gas as a refrigerant and an insulating medium, and can discharge the gas through the outlet at a temperature substantially only 15 degrees cooler than the atmospheric temperature. These tests indicate great efficiency in the control of temperatures and in the utilization of Dry Ice.

With this arrangement of parts, heat exchange is accomplished from the lower or bottom thin edge of the thin block or slab of solidified carbon dioxide resting upon or in proximity to heat exchange wall 22, and the gas of sublimation will settle within the refrigerant compartment 7 on all sides around the thin cake or slab of Dry Ice, to serve as an insulating blanket to minimize sublimation of the Dry Ice on any except the lower edge, the gas also serving to prevent infiltration of heat through the side walls of the refrigerant compartment 7. As the gas of sublimation fills the compartment, this gas will drop or flow by its natural weight through the gas escape or conducting tube 26, to fill gas space 12, and as the sublimation continues all of the gas spaces will be filled and an insulating blanket of carbon dioxide gas will be established and maintained around the refrigerating compartments 2 and 3. It has been found that the inert gas resultant from sublimation of solidified carbon dioxide is a very efficient insulator when used in this manner, and also experiments have shown that with this blanket or surrounding atmosphere of carbon dioxide gas, heat that would otherwise infiltrate through the insulation material 10 is taken up by the gas and the expanding gas carries off this heat through gas escape vent 17.

The doors 4 and 5 will of course be insulated, so that loss of efficiency is guarded against at the access side of the refrigerating compartment.

Temperature changes and variations can be accomplished within the refrigerating compartments 2 and 3, by using a thicker or thinner slab or block of solidified carbon dioxide, as in this way the relative area of the lower side of the

block or cake of refrigerant as exposed adjacent to the heat exchange wall 22 can be varied. However, I have also found that temperatures can be varied and controlled within desired limits by placing a sheet of paper or cardboard or other heat exchange insulation, as at 27, between the upper side of the heat exchange wall 22, and the lower side of the block or cake of solidified carbon dioxide. By controlling the size or area of the face of the block or cake of Dry Ice as exposed on the lower side, by interposition of heat exchange insulation material, and by variation in the number and size of the heat exchange fins 25, it is possible to obtain and maintain very accurate degrees of temperature as these may be desired in the refrigerating compartments 2 and 3, and in like manner the expenditure of energy of the solidified carbon dioxide can be expedited or retarded and the useful life of a cake or block of this refrigerant can be considerably prolonged. At the same time, there will be no extreme temperatures and no useless loss or waste of energy of the solidified carbon dioxide. Furthermore, with the parts constructed and arranged in the manner set forth, and operating as described, after the access door of one of the refrigerating compartments has been opened and the temperature has naturally elevated due to higher atmospheric temperatures, when the door is again closed circulation of air within the compartment will be accelerated and the temperature of the compartment will be very quickly restored to stability and the degree of refrigerating temperature as desired.

As stated, the air circulation stack 6 is placed substantially centrally between the refrigerating compartments 2 and 3, and the refrigerant compartment 7 and the heat exchange portions associated therewith are substantially centered within the stack, so that there is maintenance of substantially uniform circulation of air and uniform temperatures within both refrigerating compartments 2 and 3. Also, when one compartment has been opened and the other has not, there will be a quicker pick-up and quicker restoration of the desired temperature within the compartment which has been opened.

As stated, the presently illustrated apparatus of my present invention is to primarily provide for refrigeration and curing or tempering or conditioning of pies and the like, and to this end I provide removable pie-supporting racks 28 in the refrigerating compartments 2 and 3. These removable pie racks are preferably made up of wire or rod members of suitable material, with the uprights 29 adapted to fit substantially within the compartments 2 and 3 at the corners thereof and held in spaced-apart relation by cross-bar portions 30. Pie shelf or supporting rods 31 are provided in outstanding relation on each side to receive and support a pie tin or plate, after the manner shown in Fig. 8.

As stated, these pie shelf or supporting rods are extended outwardly so that they will receive the edges of pie tins or plates, and since commercial baking practices have established pies of different sizes, it is desirable that the removable racks be made in different sizes to accommodate different sizes or diameters of pies. For example, with the showing in Fig. 8, the rack will support a 10-inch pie, with the showing in Fig. 9, the rack is adapted for a 9-inch pie, and with the disclosure in Fig. 10, the rack is intended for an 8-inch pie. With the various sizes of racks, adapted for the 8-inch and 9-inch and 10-inch pies, it will be

appreciated that the pie shelf or supporting rods 31 will be spaced apart a suitable distance for the particular diameter of the pie plate or tin to be supported or rested thereon; and, since it is desirable that the pies be presented forwardly to be readily available when the access doors 4 and 5 are opened, it may be found advantageous to provide upright stop rods or bars 32 to limit inward movement of the smaller sizes of pies.

As shown in Figure 1, the door 9 closing the door opening 8 into the refrigerant compartment 7 is entirely separate and this door will remain closed at all times when the access doors 4 and 5 of the refrigerating compartments 2 and 3 are opened or operated. A lock or latch 33 is provided on the door 9, and the doors 4 and 5 of the refrigerating compartments 2 and 3 can have locks or latches 34 and 35, of any suitable and desirable type.

When my improved structure is employed for carrying or transporting pies, it may be found desirable to provide lifting and carrying handles 36, and it will also be appreciated that skids or rollers or casters can be placed on the bottom of the cabinet structure, if this be desired.

In the use and carrying out of my invention in the handling and refrigeration of pies, I have found that it is possible to transport and to handle and to store cream and custard and meringue pies at a temperature which guards against deterioration and spoilage and which inhibits or retards growth and development of micro-organisms. Thus, it has been found possible to transport and to store and to preserve the usually perishable pies in substantially oven-fresh condition for periods of several days from the baking or oven date, something which has heretofore been considered impossible.

Additionally, experiments and actual use in employment of my improved apparatus and method show that pies thus refrigerated are maintained in substantially oven-fresh condition without deterioration in consistency or appearance of meringues and whipped cream and other toppings, without separation of the filling from the crust, and without the crust becoming soggy or losing its desirable oven-fresh flaky characteristics. Thus, it has been found that with my apparatus and method an oven-fresh pie seems to be tempered or cured or maintained in the oven-fresh condition, and without deterioration in appearance or other characteristics, for a period of several days. The reason for this tempering or curing effect is not immediately known; but, sufficient tests have been conducted to show that a result is obtained which is not attainable by placing a pie in a refrigerator or in other apparatus or appliances heretofore available.

In the broad aspect, I have in effect accomplished a new cycle of refrigerating, in which a sealed refrigerant container accumulates gas of sublimation and generates pressure to force gas downwardly through a conducting pipe and into and up between the hollow side walls around the refrigerating compartments, so that the side walls are in effect converted into heat exchange walls for rapid pick-up of refrigeration in the compartment, and that at the same time the walls are insulated against infiltration of outside or atmospheric heat. With my improved apparatus and method, circulation of air within the refrigerating compartments stimulates sublimation of the Dry Ice and accordingly increases circulation of gas, and this increased cir-

culation of gas aids in rapid pick-up and refrigeration of the air within the refrigerating compartments.

In other words, the air to be cooled is refrigerated directly from the solidified carbon dioxide, and indirectly from the gas of sublimation generated by the direct contact; and, this dual refrigeration joined together gives an almost perfect result, with the spent gas discharged at a temperature only slightly above atmospheric temperature.

While I have herein shown and described only certain specific embodiments of my invention and have set forth only certain variations, it will be appreciated that many changes can be made in the form and construction and arrangement of the parts, and in the steps or procedures of carrying out the method or process, without departing from the spirit and scope of my invention.

I claim:

1. Refrigerating apparatus for use with solidified carbon dioxide comprising a double-walled cabinet structure having refrigerating compartments therein, an air circulation stack intermediate said compartments having openings in the upper and lower parts thereof through which air in the compartment is circulated through said stack, a closed refrigerant container in the upper part of the air circulation stack and having a bottom heat exchange wall exposed therein, a gas conducting tube from the upper part of the refrigerant container discharging gas of sublimation between the double walls at the bottom of the cabinet structure, and a gas escape vent from the double wall opening at the top.

2. Refrigerating apparatus for use with solidified carbon dioxide comprising a double cooling cabinet structure having a food refrigerating compartment therein, an upright air circulation stack having openings in the upper and lower parts through which air in the refrigerating compartment is circulated through said stack, a closed refrigerant is circulated through said stack, a closed refrigerant container in the upper part of the air circulation stack and having a bottom heat exchange wall exposed therein, a gas conducting tube from the upper part of the refrigerant container leading to discharge gas of sublimation between the double walls at the bottom of the cabinet structure, and a gas escape vent from the double walls near the top thereof.

3. Refrigerating apparatus for use with a flat rectangular block of solidified carbon dioxide comprising a double-walled cabinet structure having a refrigerating compartment therein, an upright air circulation stack within the compartment to be refrigerated having openings in the upper and lower parts through which air in the compartment is circulated through said stack, a flat closed refrigerant container disposed in upright relation in the upper part of the stack for the flat block of refrigerant having a bottom heat exchange wall exposed to circulation of air within the stack to have the flat block of refrigerant placed with a narrow edge thereof adjacent to the bottom heat exchange wall, a sheet of insulating sublimation retarding material interposed between the heat exchange wall and the block of refrigerant, a gas conducting tube from the upper part of the refrigerant container discharging gas of sublimation between the double walls at the bottom of the cab-

inet structure, and a gas escape vent from the double wall space opening at the top.

4. Refrigerating apparatus for use with solidified carbon dioxide comprising an upright double wall refrigerating space, an upright air circulation stack within said refrigerating space having openings in the upper and lower parts thereof through which air in the refrigerating space is circulated, a closed refrigerant container within the upper part of the circulation stack closed off from said refrigerating space and from the space between the double walls and provided with a heat exchange bottom wall exposed within the circulation stack, a gas conducting tube having an open upper end in the upper part of the closed refrigerant container and having a lower discharge end opening to the lower part of the double wall structure whereby gas of sublimation will fill the closed refrigerant container around a block of solidified carbon dioxide there- 20

in and will then enter the tube and be discharged at the bottom to fill between the double walls carrying off heat of infiltration, and a gas escape vent from the double wall space opening at the top.
